(57) **CLAIM**

The ornamental design for a wall plate for television media cables as shown and described.

DESCRIPTION

FIG. 1 is a top, front perspective view of a wall plate for television media cables showing the new design;

FIG. 2 is a top view thereof;

FIG. 3 is a front view thereof;

FIG. 4 is a bottom view thereof;

FIG. 5 is a right-side view thereof, the left-side view being a mirror image thereto;

FIG. 6 is a rear view thereof;

FIG. 7 is a top, front perspective view of an alternative embodiment of a wall plate for television media cables showing the new design;

FIG. 8 is a top view thereof;

FIG. 9 is a front view thereof;

FIG. 10 is a bottom view thereof;

FIG. 11 is a right-side view thereof, the left-side view being a mirror image thereto; and,

FIG. 12 is a rear view thereof.

The even-length broken lines in the figures represent portions of the wall plate for television media cables that form no part of the claimed design.

1 Claim, 6 Drawing Sheets
